(57) **CLAIM**

The ornamental design for a travel case with compartments for the transport of glasses and contact lenses, as shown and described.

DESCRIPTION

The file of this patent contains at least one drawing/photograph executed in color. Copies of this patent with color drawing(s)/photograph(s) will be provided by the Office upon request and payment of the necessary fee.

1. Travel case with compartments for the transport of glasses and contact lenses

1.1 is a front perspective view showing a new design for a travel case with compartments for the transport of glasses and contact lenses;

1.2 is a front perspective view thereof in an open configuration;

1.3 is a rear perspective view thereof; and

1.4 is a top plan view thereof.
